(57) **CLAIM**

The ornamental design for a cutter head for a nose hair trimmer, as shown and described.

DESCRIPTION

FIG. 1 is a top, front, right side perspective view of a cutter head for a nose hair trimmer showing my new design; FIG. 2 is a bottom, rear, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines show features of the cutter head for a nose hair trimmer that form no part of the claimed design.
